UNITED STATES PATENT OFFICE.

JAMES E. FROMAN, OF EVANSVILLE, INDIANA.

HOOD MOUNTING FOR BABY CARRIAGES.

Application filed January 5, 1922. Serial No. 527,084.

To all whom it may concern:

Be it known that I, JAMES E. FROMAN, a citizen of the United States, residing at Evansville, in the county of Vanderburgh and State of Indiana, have invented certain new and useful Improvements in Hood Mountings for Baby Carriages, of which the following is a specification.

This invention relates to hood mountings or brackets for baby carriages, the object being to provide improved means for raising and lowering the hood and securing it at any elevation; further, improved adjustable locking means for connecting the hood to the body of the carriage in such manner that it may be tilted and held at any desired angle and, also, adjusted lengthwise of the body of the carriage.

My improvements not only carry out the foregoing objects but they also contemplate the provision of an improved quick-detachable connection enabling the hood to be easily applied to, or removed from, the body.

The particular improvements represented by the various features and combinations of my invention are set forth fully hereinafter and recited in the appended claims. The showing of the invention is to be considered as illustrative, instead of restrictive, of the scope thereof as modifications may be resorted to.

In the accompanying drawings:

Figure 1 is a perspective view of a baby carriage equipped with the hood mounting constituting the invention.

Fig. 2, a detail inside view of the hood, showing the complete invention for supporting one side thereof.

Fig. 3, a detail bottom view of one of the bars.

Fig. 4, a detail, broken, side elevation of the spring, the bar, disk, and other parts in position for removal.

Fig. 5, a bottom view thereof; and

Figs. 6, 7 and 8, detail views of the clamping devices for securing the hook at different elevations.

The body of the baby carriage is shown at 1 and the hood at 2.

Bars 3 having pointed angled ends 4 are secured to the sides of the body 1 by means of said points 4. These bars have longitudinal slots 5 and enlarged openings 7.

Secured to the inside of the hood 2 on opposite sides thereof are upper and lower metal strips 8, 9, to which, in each instance,

is fastened an upright sleeve 10 which has a cut out portion 11 providing a flexible shoe 12. Secured to the strips 8, 9, is a boxing 13 connected to the sleeve by a strap 14. A handle 15 which is provided with an irregular head or cam 16 has collars 17 which retain it where journaled in boxing 13. The cam 16 bears against the shoe 12.

Slidable through the sleeve 10, in each instance, is a rod 18 which is clamped firmly to the sleeve by the shoe 12 when the handle 15 is properly operated for that purpose but which is released on swinging the handle 15 to release the shoe 12. The cam or head 16 presses against, or releases, shoe 12 according to the position of handle 15. Secured to the lower end of each rod 18 is a double or bifurcated head 19.

Journaled or pivoted to the double head 19 and lying between the sections thereof is a disk 20 which is provided with a flat extension 21 having a shoulder 22 and an end part 23 which passes through the bar 3. A cam handle 24 is pivoted at 25 to the end 80 of the part 23. Bearing against the upper face of the bar 3 is a double spring brake 27 whose ends bear on the respective sections of the double head 19. The part 23 passes through an opening in the spring 27 and the shoulder 22 bears on said double spring. Beneath the bar 3 is a washer 28 which bears against said bar and is engaged by the cam on the handle 24. The washer 28 is of a shape adapting it to pass through the hole 90 7 when the handle 24 is loose and said washer is tilted so that it will go through said hole in an endwise movement. The handle 24 is also of a shape and dimension to pass through the hole 7. Consequently 95 provision is made for taking off the top 2 by releasing the handle 24 and passing it through the hole 7, together with the washer 28, the bars 3 then remaining on the body 1.

My improvements provide for vertical adjustment of the hood 2 on the rods 18 regardless of the angle to which said rods are tilted. Provision is also made for clamping the rods 18 at any angle and, further, for sliding said rods, with the hood 2, forwardly 105 or rearwardly of the body.

What I claim is:

1. In a hood mounting for baby carriages, the combination with the body of the carriage, of bars carried thereby having slots provided with enlarged openings, a hood, supports connected to the hood

which have heads, other heads pivoted to the heads aforesaid and provided with extensions or shanks passing through the slots in the bars, spring means engaged by said extensions or shanks and which bear on the heads first named, and locking cam levers connected to the extension or shanks which are adapted to secure the latter to the bars and to tension the springs, said levers being adapted for removal through the enlarged openings, whereby the hood and its attaching means may be bodily removed or detached from the bars.

2. In a hood mounting for baby carriages, the combination with a body, of horizontally arranged bars carried thereby, having openings, a hood, upwardly extending rods, clamp-slides to which the rods are pivoted, said slides being adjustably mounted on the top of said bars, means being provided beneath the bars for securing the clamp-slides where adjusted and fastening the rods in any position to which they may be swung, and releasable clamping devices 25 for securing the opposite sides of the hood

to the rods so that the hood may be raised or lowered on said rods, said securing means being removable through the openings in the bars, whereby the hood may be raised, tilted, moved bodily forward or rearward, 30 or completely detached, together with said clamp slides and rods, from said bars.

3. In a hood mounting for a baby carriage, the combination with attaching devices adapted to be applied to the sides of the body of the carriage, of rods for supporting the hood, disks, each having an extension which passes through one of the attaching devices, tensioning means carried by said extensions and engageable with the 40 attaching devices, heads carried by the rods which are pivotally connected to the aforesaid disks, and brake springs which bear on the heads carried by the rods and also against the attaching devices, said brake 45 springs being released or tightened by operating the tensioning means.

In testimony whereof I affix my signature.

JAMES E. FROMAN.
